CLAIM

The ornamental design for a display screen or portion thereof with icons, as shown and described.

DESCRIPTION

FIG. 1 is a front views of a display screen or portion thereof with icons showing our new design according to a first embodiment.

FIG. 2 is a front views of a display screen or portion thereof with icons showing our new design according to a second embodiment.

FIG. 3 is a front views of a display screen or portion thereof with icons showing our new design according to a third embodiment.

FIG. 4 is a front views of a display screen or portion thereof with icons showing our new design according to a fourth embodiment.

FIG. 5 is a front views of a display screen or portion thereof with icons showing our new design according to a fifth embodiment.

FIG. 6 is a front views of a display screen or portion thereof with icons showing our new design according to a sixth embodiment.

FIG. 7 is a front views of a display screen or portion thereof with icons showing our new design according to a seventh embodiment.

FIG. 8 is a front views of a display screen or portion thereof with icons showing our new design according to an eighth embodiment.

FIG. 9 is a front views of a display screen or portion thereof with icons showing our new design according to a ninth embodiment.

FIG. 10 is a front views of a display screen or portion thereof with icons showing our new design according to a tenth embodiment.

FIG. 11 is a front views of a display screen or portion thereof with icons showing our new design according to an eleventh embodiment.

FIG. 12 is a front views of a display screen or portion thereof with icons showing our new design according to a twelfth embodiment.

FIG. 13 is a front views of a display screen or portion thereof with icons showing our new design according to a thirteenth embodiment.

FIG. 14 is a front views of a display screen or portion thereof with icons showing our new design according to a fourteenth embodiment.

FIG. 15 is a front views of a display screen or portion thereof with icons showing our new design according to a fifteenth embodiment.

FIG. 16 is a front view of a display screen or portion thereof with icons showing our new design according to a sixteenth embodiment.

FIG. 17 is a front view of a display screen or portion thereof with icons showing our new design according to a seventeenth embodiment.

FIG. 18 is a front view of a display screen or portion thereof with icons showing our new design according to an eighteenth embodiment.

FIG. 19 is a front view of a display screen or portion thereof with icons showing our new design according to a nineteenth embodiment.

FIG. 20 is a front view of a display screen or portion thereof with icons showing our new design according to a twentieth embodiment.

FIG. 21 is a front view of a display screen or portion thereof with icons showing our new design according to a twenty-first embodiment.

FIG. 22 is a front view of a display screen or portion thereof with icons showing our new design according to a twenty-second embodiment.

FIG. 23 is a front view of a display screen or portion thereof with icons showing our new design according to a twenty-third embodiment.

FIG. 24 is a front view of a display screen or portion thereof with icons showing our new design according to a twenty-fourth embodiment.

FIG. 25 is a front view of a display screen or portion thereof with icons showing our new design according to a twenty-fifth embodiment.

FIG. 26 is a front view of a display screen or portion thereof with icons showing our new design according to a twenty-sixth embodiment.

FIG. 27 is a front view of a display screen or portion thereof with icons showing our new design according to a twenty-seventh embodiment.

FIG. 28 is a front view of a display screen or portion thereof with icons showing our new design according to a twenty-eighth embodiment.

FIG. 29 is a front view of a display screen or portion thereof with icons showing our new design according to a twenty-ninth embodiment; and,

FIG. 30 is a front view of a display screen or portion thereof with icons showing our new design according to a thirtieth embodiment.

The outermost broken lines in the Figures show a display screen or portion thereof and form no part of the claimed design. The remaining broken lines showing portions of the graphical user interface form no part of the claimed design.
